Primary Examiner — Selina Sikder(74) *Attorney, Agent, or Firm* — SAIDMAN DesignLaw Group**CLAIM**

The ornamental design for a light emitting diode, as shown and described.

DESCRIPTION

FIG. 1 is a front, top, left side perspective view of a light emitting diode showing my new design;

FIG. 2 is a rear, bottom, right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines illustrate environmental structure and form no part of the claimed design.
